METHOD AND APPARATUS FOR TREATING PILE FABRICS

Application filed January 28, 1932. Serial No. 589,395.

This invention relates to the finishing of pile fabrics and is concerned more particularly with an improved method and apparatus for treating the surface of the fabric to smooth and clean it, open up the bunches of tufts, remove the loose fibres, and polish or luster the tuft yarns. The treatment of such fabrics by my method so as to obtain a better coverage by the face yarns, greatly improves the appearance and softens the face of the fabric.

In the manufacture of pile fabrics, it is customary after weaving and trimming to treat the fabric to improve its appearance and obtain better coverage by the face yarns, and the methods heretofore commonly used have involved steaming and brushing the fabric, either with bristle or wire brushes, to open up the tufts of pile yarn and remove the loose fibres. These methods are partially successful in accomplishing the desired purpose, but they do not luster or polish the face yarn of the fabric to any appreciable extent and hence do not give the fabric the desired sheen or silky appearance.

The present invention is, accordingly, directed to the provision of a novel method and apparatus which affords the advantages mentioned, including the polishing or lustering of the face yarn, in a simple and efficient manner. In general, the new method comprises subjecting the fabric to brushing, heating, and ironing, carried on preferably by revolving rolls, each of which carries both brushing sections and ironing sections arranged alternately, so that the several operations are consecutively performed. In carrying out the method, a number of rolls may be employed, and they are advantageously rotated in opposite directions so that the pile is acted on from opposite sides.

For some grades of fabric the ironing and brushing treatment is performed upon the fabric, preferably in dry condition, but with other grades it may be desirable to moisten the fabric before or during the treatment, for example, with water, steam, or a chemical solution, for instance, of an alkaline reaction. The new method and apparatus may be used for finishing the fabric, either

dry or moistened, and produces a lustrous finish and the other effects previously mentioned.

For a better understanding of the preferred apparatus for practising the invention, reference may be had to the accompanying drawing, in which;

Fig. 1 is a vertical sectional view through the apparatus with parts omitted to make clear the novel features;

Fig. 2 is a sectional view through one of the rolls; and

Fig. 3 is a wiring diagram showing how the ironing sections are heated electrically.

The apparatus with which I prefer to practice the method of my invention is illustrated in the drawing as comprising a series of platens over which the fabric is passed and a series of rotatable cylinders, each operating on the fabric as it passes over a platen, and each provided with a plurality of ironing and brushing sections arranged in alternations around the cylinder. In carrying out the method, the fabric is fed face up between the platens and cylinders successively and each cylinder subjects the pile surface to alternate brushing and ironing operations.

In the apparatus illustrated, the fabric to be treated is drawn from a roll 10 supported upon rollers 11, and passes over a roller 12 to platens 13, above which are cylinders 17, each operating on the fabric as it passes over one of the platens.

The cylinders are of similar construction and each comprises a cylindrical shell 22 mounted on a shaft 23 and having two brush sections 24 extending axially of the cylinder on opposite sides thereof and held in place by bolts 25. The brushing surface of these sections may be wire brushes and are preferably made of material known as card clothing. Between the two brushes and also located on opposite sides of the cylinder are two ironing plates 26 similarly extending axially of the cylinder and held in place by bolts 28. Vent openings 22' are located between the brushes and ironing devices. The ironing plates may be heated in any desired manner, for instance, by steam or

by electricity, and in the construction illustrated, there are two electrical heating elements 29 beneath each plate 26. All the heating elements are connected in parallel 5 to a pair of slip rings 30 mounted at one end of the cylinder 22 on the shaft 23, and the slip rings are supplied with current from a source of power 32 through brushes 33.

10 After passing over the last platen 16, the fabric passes over a spiked roller 34 which serves to draw the fabric through the apparatus and the fabric is then wound into a roll 35 supported by rollers 36.

15 The cylinders 22 may be driven in any desired manner, but I prefer to drive the alternate cylinders in opposite directions since this spreads the pile yarns and causes both sides thereof to be brushed and ironed 20 and generally produces the most desirable results.

The use of cylinders having both brushing and ironing sections is especially desirable because of the rapid alternation of ironing 25 and brushing which is thus obtained. This rapid alternation makes certain that the pile will be heated when it is brushed and greatly lessens the likelihood of scorching or burning the pile as the pile is rearranged by the brushes between each pair of successive contacts with the ironing members. The protection against scorching is particularly important if the pile is ironed 30 dry for when so ironed it would scorch 35 easily if these precautions were not taken.

When the fabric is to be treated in dry condition, the apparatus may be used in the form illustrated, but if the surface of the fabric is to be moistened, the moistening 40 may be effected by any suitable means before or during the treatment. For example, steam may be applied to the fabric by means of one or more perforated or slotted pipes arranged to discharge the steam upon 45 the surface, while water or chemical solutions are preferably applied by spray nozzles. In some instances, both steam and water or chemical treatments may be used in which event a suitable combination of 50 discharge devices will be employed.

In practising the new method by the apparatus described, the fabric is repeatedly brushed and ironed, first in one direction and then in the other, until all of the pile 55 yarns have been thoroughly untwisted and brushed and ironed on all sides, and the loose strands all removed. The result is a luxurious fabric in which the face yarns have a beautiful luster and form an even, smooth 60 pattern.

I claim:

1. A method of finishing pile fabrics which comprises moistening the pile surface with an alkaline solution, alternately brushing 65 and ironing the pile surface by elements

moving in one direction relative to the pile, and thereafter alternately brushing and ironing the pile surface by elements moving in the opposite direction relative to the pile.

2. Apparatus for finishing pile fabrics 70 comprising a rotatable cylinder, an arcuate ironing section mounted on the cylinder, and an arcuate brush section mounted on the cylinder.

3. Apparatus for finishing pile fabrics 75 comprising a rotatable cylinder, this cylinder having mounted on its periphery an ironing section and a brush section, means for supporting a fabric in contact with said sections as the cylinder rotates, and means 80 for advancing the fabric over the supporting means.

4. Apparatus for finishing pile fabrics comprising a rotatable cylinder, a plurality 85 of ironing sections and a plurality of brush sections arranged in alternation upon the periphery of the cylinder, means for supporting a fabric to be acted on by said sections, and means for advancing the fabric over the supporting means. 90

5. Apparatus for finishing pile fabrics comprising a rotatable cylinder, a pair of ironing sections having arcuate surfaces arranged in alternation with a pair of brush sections on the surface of the cylinder, 95 means for supporting a fabric to be acted on by said sections, and means for moving the fabric over the supporting means.

6. Apparatus for finishing pile fabrics comprising a rotatable cylinder, an ironing element on the surface of said cylinder, 100 means for heating said element, a brush element mounted on the surface of the cylinder, means for supporting a fabric against the cylinder, and means for moving the fabric over the supporting means. 105

7. Apparatus for finishing pile fabrics comprising a plurality of rotatable cylinders each having an ironing element and a brush section mounted on its surface, means for 110 rotating alternate cylinders in opposite directions, and means for advancing a fabric to be acted on successively by said cylinders.

8. Apparatus for finishing pile fabrics comprising a plurality of rotatable cylinders 115 each having ironing elements and brush sections arranged in alternation on the surface of said cylinder, means for heating said ironing elements, means for rotating alternate cylinders in opposite directions, and means for advancing a fabric into contact with said cylinders successively. 120

9. Apparatus for finishing pile fabrics comprising a plurality of rotatable cylinders 125 each having ironing elements and brush sections mounted thereon in alternation, means for rotating alternate cylinders in opposite directions, a fabric support associated with each cylinder, and means for advancing a fabric over the supports successively. 130

10. Apparatus for finishing pile fabrics comprising a plurality of platens, means for moving a fabric over the platens, a cylinder associated with each platen and acting on said fabric as it passes over said platen, said cylinder having a wire brush and an ironing member mounted thereon, and means for rotating alternate cylinders in opposite directions.

10 11. In apparatus for finishing pile fabrics, a rotatable cylinder for acting on the fabric, said cylinder having ironing elements with arcuate surfaces and brush sections arranged thereon in alternation, and electrical heating elements for heating said ironing elements.

12. A method of finishing pile fabrics which comprises alternately brushing and ironing the face of the fabric by elements moving in one direction relative to the fabric and thereafter alternately ironing and brushing the fabric by elements moving in the opposite direction to separate the strands of face yarn, remove loose strands and polish the fixed strands, and moistening the fabric with an alkaline treating fluid before the brushing and ironing operations are finished.

13. Apparatus for finishing pile fabrics comprising a plurality of rotatable cylinders each having ironing elements and brush sections arranged in alternation on the surface of said cylinder, means for heating said ironing elements, means for rotating alternate cylinders in opposite directions, means for advancing a fabric into contact with said cylinders successively, and means for moistening the fabric with a treating fluid.

In testimony whereof I affix my signature.
